Inventor:
Eugene J. Post

United States Patent Office.

EUGENE J. POST, OF VIENNA, NEW JERSEY.

Letters Patent No. 61,633, dated January 29, 1867.

IMPROVED HAT AND COAT HOLDER.

The Schedule referred to in these Letters Patent and making part of the same.

TO ALL WHOM IT MAY CONCERN:

Be it known that I, EUGENE J. POST, of the village of Vienna, in the county of Warren, in the State of New Jersey, have invented certain new and useful improvements in the Apparatus for Holding and Preserving Hats when not in use, and the application thereof; and the following is a full, clear, and exact description of the same, reference being had to the accompanying drawings, making a part of this specification.

Figure 1 represents a view of a stationary hat-holding apparatus and coat hook combined.

Figure 2 represents a view of an adjustable hat-holding apparatus and coat hook combined.

Figure 3 represents the hat-holding apparatus detached.

The object of my invention is to furnish a cheap, durable, and substantial apparatus for the purpose of preserving and holding hats when not in use in halls, offices, wardrobes, and other places where the hat might be blown, thrown, or knocked down, forming, when used in combination with the coat hook, a certain and perfect hat holder, as the hat must be lifted bodily out of the holder before it can be removed.

My invention consists in forming a curve or ledge of wire, metal, or cleats of wood of suitable form or device to support the hat by the brim, to be attached to or in combination with a coat hook, hinged or stationary.

To enable others skilled in the art to make and use my invention, I will describe it more fully, referring to the drawings and to the letters marked thereon.

The combined hat holder and coat hook may be constructed, as shown in fig. 1, of wire so shaped as to form an eye, *b*, or eyes by which to secure it to the wall or other suitable place, the lower portion formed into a hook, *c*, on which to suspend a coat or other garment, the upper portion formed into horns or curves in which the hat slides and is held by the brim. The combined adjustable hat holder and coat hook, as shown in fig. 2, is constructed as a bracket and hook, *D*, of metal to be secured in any desirable place, the upper part of the bracket *E* projecting at right angles from the wall, and so formed as to make a hinge, *e*, in which the centre portion of the horns *a a*, a Y-shaped wire is grasped, between which gripes or hinges, *e*, on the hat holder, horns or Y-shaped wire *a a*, a projecting arm is shown, *f*, which supports said hat holder, horns, or Y-shaped wire in a horizontal position by bearing up against the under side of the bracket projection *E*, the hinged or adjustable arrangement allowing the hat while held in the holder to be turned up against the wall, thus securing the hat in the same position as if held upon a pin.

It will readily be seen that the advantages to be derived from the use of my invention in regard to comfort, and the care and preservation of hats are innumerable. In halls, rooms, or offices, by the use of my invention, the hat is perfectly secure, not liable to be knocked down by others, cannot be blown down, and, by the peculiar shape and action of the hat holder, neither roughing the nap or wearing upon the hat.

Having thus fully described my invention, what I claim, and desire to secure by Letters Patent, is—

I claim the arrangement and combination of the hat holder and preserver with the coat hook and bracket, whether stationary or adjustable, substantially as and for the purposes herein set forth.

EUGENE J. POST.
